KNITTING DEVICE

Mac Buxbaum and Moe Levensfeld,
Flushing, N. Y.

Application March 8, 1952, Serial No. 275,581

7 Claims. (Cl. 66—8)

1

This invention relates to a knitting device, and more particularly to a toy knitting device for producing a continuous tubular fabric from a single strand of yarn or the like.

Apparatus of this type heretofore proposed have had to be held manually in a substantially vertical position in order for the knitted tubular cord to be formed properly by the knitting device. This has proved unsatisfactory for a number of reasons among which is that it may be quite tiring and persons who desire to use the apparatus who are, for example, bedridden, are put to a distinct disadvantage.

Furthermore, apparatus of this character heretofore suggested has produced a knitted tubular cord of substantially uniform cross section providing the strand from the source of supply is of a uniform cross section.

One of the objects of the present invention is to form a knitted tubular cord of varying cross sectional area from, for example, a yarn having a substantially uniform diameter.

A further object of the invention is to provide a knitting device which can be manually operated satisfactorily regardless of the attitude of the device.

Various, further and more specific objects, features and advantages of the invention will clearly appear from the detailed description given below taken in connection with the accompanying drawings which form a part of this specification and illustrate, by way of example, preferred arrangements of apparatus for carrying out the invention. The invention consists in such novel combinations of features as may be shown and described in connection with the device herein disclosed.

In the drawings:

Fig. 1 is a side elevation, partly in section and with parts broken away, of a device embodying one form of the present invention;

Fig. 2 is a perspective view of the apparatus shown in Fig. 1;

Fig. 3 is a top plan view of the device shown in Figs. 1 and 2; and

Fig. 4 is a sectional view taken substantially along lines 4—4 of Fig. 1.

Referring to the drawings in greater detail, the novel knitting device is constituted by a first member 10 in the form of a hollow cylindrical casing having a passageway 10a therethrough in which is positioned for rotation therein a second member 11 comprising a needle guide which is mounted coaxially thereof. The second member or needle guide 11 is of hollow cy-

2

lindrical form and has a passage 11a therethrough and also is provided with suitable needle guide means which are well shown in Fig. 3 at 12 and 13, such guide means comprising diametrically opposed channel forming members 12a, 12b, and 13a, 13b, respectively, extending longitudinally of the member 11 and forming channels in which latch type knitting needles 14 and 15, respectively, are axially shiftable. The needles 14 and 15 are respectively provided with end hooks 14a, 15a and pivotable latches 14b, 15b which operate in a well known manner. The needles 14 and 15 also are respectively provided with radially outwardly extending fingers 14c and 15c which engage a cam groove 16 formed in the surface of the passage 10a. In order to effect reciprocative movement of the needles 14 and 15 the aforementioned groove 16 is oblique to the axis of the members 10 and 11 whereby angular movement of member 10 relative to member 11 will produce such reciprocation. The groove 16 is so disposed in the passageway 10a that such reciprocation causes the heads of the needles 14 and 15 to rise above the upper edges 10b and 11b of the members 10 and 11, respectively, and thus into a yarn engaging position. Thereafter the needle heads descend to a position below such upper edges. Such upper and lower limits of motion of the needles are shown with respect to the hook 15a which is at its highest position, and hook 14a at its lowest position.

As viewed in Fig. 3, the inner cylindrical casing or inner member 11 is of somewhat smaller outer diameter than the inner diameter of the passage 10a, such diameter being measured, for example, commencing at point 11c. However, the outer diameter of the member 11 as measured, for example, across members 12a and 13b, is only slightly less than the inner diameter of such passageway adjacent the groove 16 whereby suitable clearance is effected therebetween. If desired, suitable longitudinally extending ribs 11d and 11e may be provided preferably diametrically opposed and situated, for example, 90° from the needles 14 and 15.

We have found it desirable, in order suitably to tension a strand of yarn 17 as it is fed to the device, to provide a sinuous path therefor by means of an upstanding arm 18 preferably integral with the cylindrical member 10, the arm having passages 19 and 20 through which moves the yarn 17. Below the arm 18 there is formed a passage 21 through which the yarn 17 initially is led from a source of supply and

thence outwardly through the passage 20 and thence again inwardly through the passage 19 and thence to the needles. Of course, if desired, the passage 21 through the cylindrical member 10 can be formed in a portion of member 10 above the level of the upper edge 10b (Fig. 2) if desired.

In order to facilitate easy manual operation of the knitting device and to vary the thickness of a knitted cord, novel means are provided for grasping and pulling outwardly upon such a tubular cord. The latter, of course, is formed by the crocheting-like action of the needles 14 and 15. Such tubular cord is shown at 22. Such novel means, in the form shown, are constituted by: a base member 23 which preferably is of cylindrical conformation and which embraces and is secured to a lower or depending portion 11c of the cylindrical member 11. The periphery of the base member 23 extends radially outwardly beyond the periphery of the first-mentioned cylindrical member 10 thereby facilitating the grasping of one of the members 10 or 11 and the rotating of the other member. A pair of hollow tubular members 24 and 25 are provided in each of which is formed a longitudinally extending slot 24a and 25a and also in each of which is positioned a coil spring, such springs being respectively indicated at 26 and 27. A spring yoke cooperates jointly with both of the springs 26 and 27 for urging the tubular cord 22 outwardly and away from the member 11, such spring yoke being indicated at 28 and having a suitable hook, as at 29, secured centrally thereof intermediate the springs 26 and 27. Such hook, of course, can engage the cord 22 and urge same outwardly under the influence of the springs 26 and 27. The spring yoke 28 is slidable within the aforesaid slots 24a and 25a and preferably has secured on opposite extremities thereof cylindrical members 28a and 28b for moving within the cylindrical passages within the tubular members 24 and 25.

The springs 26 and 27, in the form shown, are interposed between the base 23 and the spring yoke 28, such springs being of the so-called compression type which are distorted by compressing same. However, it is, of course, possible to interpose such springs between the spring yoke 28 and a cross piece 30 which is secured to the outer extremities of the tubular members 24 and 25, such springs, of course, being extended or expanded instead of compressed in order to distort same for the pulling of the cord 22.

In operation the strand of yarn 17 is led through the openings 21, 20 and 19, as shown in Fig. 2, and is engaged with one of the needles 14 or 15. The cylindrical members 10 and 11 are rotated relative to one another whereby the yarn is formed by crocheting-like operation into the aforementioned tubular cord 22. The needle guide 11 should be turned in a clockwise direction (Fig. 3) in order to form the cord 22. In order to facilitate the formation of the cord, a length of the strand 17 may, at the outset, be led through the passage 11a (Fig. 1) and a loop formed therein for engagement with the hook 29 and thereafter the strand 17 can be engaged by the needles 14 and 15 in a well known manner. The springs 26 and 27, of course, are distorted to a desired degree before connecting the hook 29 with such loop. After a length of the cord 22 has been formed sufficiently long to extend below the base 23 (Fig. 1), the hook 29 can, of course, be disengaged from said loop and engaged with the

cord. As the thrust upon the cord 22 progressively diminishes as the springs 26 and 27 gradually lengthen, the "tightness" of the knitting will gradually diminish and the cross sectional area of the knitted cord will vary. That is, the cross sectional area of such cord will be relatively smaller when knitted under a high thrust existing when the springs are distorted (or compressed) to a high degree as compared to the cross sectional area of the cord formed when the springs 26 and 27 are distorted a lesser amount. Thus a desired artistic effect due to varying thickness can be obtained by so varying the thrust upon the cord and articles such as rugs or mats made therefrom can have imparted thereto a wider variety of shape and appearance.

If desired, the cross piece 30 may have a central aperture 30a therein through which the cord 22 may pass.

While the invention has been described with respect to a certain preferred example which has given satisfactory results it will be understood by those skilled in the art, after understanding the invention, that various changes and modifications can be made without departing from the spirit and scope of the invention and it is intended, therefore, in the appended claims to cover all such changes and modifications.

What is claimed is:

1. A device for forming tubular cords of varying cross section from yarn or the like comprising in combination: a first member having a passage therethrough; a second member comprising a needle guide mounted in said first member for angular movement within the passage formed therein, said second member having a passageway therethrough and diametrically opposed guide means positioned thereon, a pair of needles positioned one in each of said guide means, means for reciprocating said needles when one of said members is rotated relative to the other member; and spring means operatively associated with said second member for urging axially away from said member a cord in response to the reciprocation of said needles, said spring means comprising: a pair of springs positioned on each side of said passageway, a spring yoke extending therebetween, and means for securing such cord to said spring yoke.

2. A device for forming tubular cords of varying cross section from yarn or the like having in combination: a first member having a passageway therethrough; a second member comprising a needle guide mounted in said first member for angular movement within the passage formed therein, said second member having diametrically opposed guide means positioned thereon, a pair of needles positioned one in each of said guide means, means for reciprocating said needles when one of said members is rotated relative to the other member; and spring means operatively associated with said second member for urging axially away from said member a cord in response to the reciprocation of said needles, said spring means comprising: a pair of slotted spring guide tubes, a pair of springs one in each tube, a spring yoke extending between said springs and drivably associated with both, and means for securing the cord to said spring yoke.

3. In a device for knitting a cord from a single strand, a first member having a cylindrical passage therethrough and having a camming groove formed in the surface of said cylindrical passage; a second member mounted within said passage, said second member having a pas-

sageway therethrough and also having a pair of diametrically opposed guide means on the outer surface thereof for guiding a pair of latch needles, one in each guide means, each of said needles having an outwardly radially extending protrusion thereupon for engaging said camming groove, said needles being reciprocable in response to relative angular movement of said members; a base secured to said second member; a spring tube secured to said base; and spring means within said spring tube, said spring means having a hook for grasping such cord knitted by the knitting device, such spring means being distortable in response to movement of said hook means near to said base for grasping the cord.

4. In a device for knitting a cord from a single strand, a first member having a cylindrical passage therethrough and having a camming groove formed in the surface of said cylindrical passage; a second member mounted within said passage, said second member having a passageway therethrough and also having diametrically opposed guide means on the outer surface thereof for guiding a pair of needles, one in each guide means, each of said needles having an outwardly radially extending protrusion thereupon for engaging said camming groove, said needles being reciprocable in response to relative angular movement of said members; and spring means operatively associated with said second member, said spring means having a base extremity fixed relative to said second member and having an opposite extremity provided with hook means for engaging said cord, such spring means being distortable in response to movement of said hook means near to said second member for so engaging the cord.

5. In a device for knitting a tubular fabric, a first member having a cylindrical passage therethrough and having a camming groove formed in the surface of said cylindrical passage; a second member mounted within said passage; a pair of latch needles; said second member having a passageway therethrough and also having diametrically opposed guide means on the outer surface thereof for guiding said pair of latch needles, one in each guide means, each of said needles having an outwardly radially extending protrusion thereupon for engaging said camming groove; a base secured to said second member, said base comprising a handle which may be grasped for effecting angular movement of one of such members relative to the other; an arm secured to said base; and spring means operatively associated with said arm, said spring means having a base extremity fixed relative to said arm and having an opposite extremity provided with hook means for grasping such tubular fabric knitted by the knitting device, such

spring means being distortable in response to movement of said hook means to a position near to said base.

6. A device for knitting a tubular cord from a single strand, an outer casing; an inner casing coaxial with and journaled for rotation in the casing first mentioned and having a pair of diametrically opposed longitudinal extending grooves therein; a pair of needles positioned one in each of said grooves, said needles having projections thereupon which extend outwardly of such grooves; said outer casing having a camming groove formed on the inner surface thereof; said projections on said needles engaging said groove, whereby said needles are reciprocable in response to angular motion of one casing relative to the other; arm means rigidly secured to said inner cylindrical member; and resilient means associated with said arm means and having a hook secured thereto for engaging such cord and pulling same, said resilient means being distortable by urging said hook to a position adjacent said inner casing whereby the hook can engage such cord.

7. A device for knitting a strand into a cord of substantially tubular form having in combination, an outer casing having a cylindrical passage therethrough; an inner hollow cylindrical casing coaxial with and journaled for rotation in the casing first mentioned and having a pair of diametrically opposed longitudinally extending needle guides therein; a pair of needles positioned one in each of said guides, said needles having projections thereupon which extend outwardly of such guides; said outer casing having a camming groove formed in the surface of the passage thereof, said projections on said needles engaging said groove, whereby said needles are reciprocable in response to angular motion of one casing relative to the other; said outer casing having perforations formed therein through which yarn can pass prior to engagement by said needles; an arm rigidly secured to said inner casing; and spring means associated with said arm and having a hook secured thereto for engaging the tubular cord, said spring means having a base extremity thereof fixed and an opposite extremity thereof mounting said hook, said spring being distortable by urging said hook to a position adjacent said inner casing whereby the hook can engage the tubular cord.
